SQUARING TOOL

Joseph F. Doud, Buffalo, N. Y.

Application November 17, 1949, Serial No. 127,981

3 Claims. (S)

CHAPTERS.

1. *Introduction*

This in

1. Introduction

This invention relates to certain new and useful improvements in squaring tools of the type used by toolmakers, machinists and the like.

It has for its primary object to provide a tool of this character which is so designed and constructed as to enable the toolmaker himself to correct and reset the tool should it become out of true and eliminate the time and expense of returning it to the factory for that purpose.

Another object of the invention is to provide a squaring tool having simple, novel and inexpensive means for adjustably and securely connecting the blade and head portions of the tool to each other and in such a manner that any adjustment for correction of its misalignment can be made easily and readily and in a minimum period of time.

Other features of the invention reside in the construction and arrangement of parts herein-after described and particularly pointed out in the appended claims.

In the accompanying drawings:

Figure 1 is a perspective of the squaring tool embodying my invention. Figure 2 is an enlarged fragmentary side elevation thereof. Figure 3 is a transverse vertical section taken on line 3—3, Figure 2. Figure 4 is a horizontal section taken on line 4—4, Figure 2. Figure 5 is a fragmentary perspective view of the tool-blade.

Similar characters of reference indicate corresponding parts throughout the several views.

My invention has been shown in connection with the usual type of toolmaker's square consisting of a head 16 and blade 11 disposed at right angles thereto. As presently marketed, when these tools require correction because of becoming out of true or misaligned, say from five to ten thousandths out of normal, it is necessary to send them back to the factory for adjustment.

The purpose of my invention is to provide for the adjustment of the tool by the toolmaker himself and thereby save the time and expense of sending it to the factory.

The head 10 is provided at its upper end with a recess or mortise defining a blade-backing portion 12 and an upwardly-facing, truly-squared shoulder 13 against which the inner or lower chamfered edge of the blade 11 rests or abuts to form a true right angle. The blade is secured transversely to the head preferably by socket-headed bolts 14 disposed in diagonal fashion in the manner shown in Figures 1 and 2. An adjusting screw 15 is provided for correctively adjusting and clamping the blade in proper relation to its head should it accidentally become mis-

aligned. This screw is disposed centrally and vertically or longitudinally of the head in a plane between the fastening bolts 14 with its threaded shank engaging a tapped opening 16 in the upper portion of the tool-head adjacent its blade-bearing face and with the socketed-head 17 of the screw engaging an alining counter bore 18 whose peripheral side portion facing the blade 10 is open, as shown in Figure 4, for the lateral projection therethrough of the companion side of the screw-head.

Formed in the inner head-engaging face of the blade is a recess 19 in opposing registering relation with the open side of the counter bore 18 and of such dimensions as to be engaged by the adjoining side or peripheral portion of the adjusting screw head 17, as shown in Figures 3 and 4, so that when such screw is turned down it will abut the bottom edge of the blade-recess and uniformly force the blade edgewise and snugly and firmly against the squared shoulder 13 of the tool-head.

When correction of the tool becomes necessary, the fastened bolts 14 are loosened and the adjusting screw 15 is first relieved and then screwed home with its head-forming shoulder abutting against the bottom edge of the blade-recess 19 to properly and correctively align the bottom edge of the blade 11 and draw it snugly against the head-shoulder 13, after which the fastening bolts are screwed home to securely retain the blade in its proper, true angular relation to the head 10. In practice, after loosening the bolts 14 and the adjusting screw, the tool is checked by lining it up with a so-called master cylinder or gage block and using a tenth indicator for checking the blade at each end, after which the adjusting screw is properly set and the fastening screws tightened.

I claim as my invention:

1. A squaring tool, comprising a blade, a head mortised at its upper end to define a blade-backing portion and an upwardly-facing squared shoulder against which the lower edge of the blade is adapted to abut, a pair of substantially diagonally-disposed screw means for transversely fastening the blade to the head, said blade having a recess between its upper and lower edges and in that side thereof facing the backing portion of the head, and an adjusting screw disposed centrally in the upper end of said tool-head at right angles to and between said transverse screw means and having its head extending at one side thereof into register with said blade-recess, one or the other of said diagonally-disposed screw

means serving as a fulcrum during the adjustment of the blade.

2. A squaring tool, comprising a blade, a head mortised at its upper end to define a blade-backing portion and an upwardly-facing squared shoulder against which the lower edge of the blade is adapted to abut, a pair of substantially diagonally-disposed screw means for transversely fastening the blade flatwise against the backing portion of the head, said blade having a recess in that side thereof facing and shrouded by said head-backing portion and the head having a tapped opening disposed centrally and vertically in the upper end thereof in a plane between said screw means and terminating in its blade-backing portion in an alining counter bore in exposed registering relation to said blade-recess, and an adjusting screw disposed in said tapped opening and having its head in engagement with said blade-recess.

3. A squaring tool, comprising a blade having a recess in the inner face of its attaching end,

a head mortised at its upper end to define a blade-backing portion and an upwardly-facing squared shoulder against which the lower edge of the blade is adapted to abut, a pair of substantially diagonally-disposed screw means for transversely fastening the blade to the head, and an adjustable screw disposed centrally in the upper end of the tool-head at right angles to and between said transverse screw means and with its head engageable with the blade-recess for drawing the blade edgewise in squared relation against said head-shoulder.
